UNITED STATES PATENT OFFICE.

HERBERT S. MILLS, OF CHICAGO, ILLINOIS, ASSIGNOR TO MILLS NOVELTY COMPANY,
OF CHICAGO, ILLINOIS, A CORPORATION OF ILLINOIS.

COIN-CONTROLLED MECHANISM.

1,190,934.

Specification of Letters Patent. Patented July 11, 1916.

Application filed August 2, 1915. Serial No. 43,170.

To all whom it may concern:

Be it known that I, HERBERT S. MILLS, a citizen of the United States, residing at 221 South Green street, Chicago, in the county of 5 Cook and State of Illinois, have invented a new and useful Improvement in Coin-Controlled Mechanism, of which the following is a specification.

My invention relates more particularly to 10 improvements in coin-controlled mechanism for operating a movable member in one direction to perform a certain operation and permit said member to automatically return to normal position; and my object, generally 15 stated, is to provide a novel, simple and positively operating construction of the character set forth, which may be manufactured comparatively economically and which will be reliable in operation.

20 I have devised my invention for use more particularly in a perfume-vending machine wherein the pump for compressing air to be supplied to the atomizers, is operated by my improved mechanism, and therefore have 25 illustrated it in this connection, though without any intention of wishing to be understood as limiting it to such use.

Referring to the accompanying drawings, 30 Figure 1 is a view in front elevation of a coin-controlled perfume-vending machine constructed according to my invention. Fig. 2 is a view in rear elevation of the machine shown in Fig. 1, with the back of the casing removed and a portion of the inner partition 35 broken away. Fig. 3 is an enlarged section taken at the line 3 on Fig. 2, and viewed in the direction of the arrow, this view showing the parts of the machine in their normal position, with a coin deposited in the machine.

40 Fig. 4 is a view like Fig. 3, showing the positions assumed by the parts of the machine after the mechanism has been operated and just before the operating lever has been depressed sufficiently far to release the coin and 45 release the piston of the air pump. Fig. 5 is a section taken at the line 5 on Fig. 4, and viewed in the direction of the arrow. Fig. 6 is an enlarged section of the upper end of one of the similar perfume containers, together 50 with the atomizing mechanism therefore, a portion of the casing of the machine being shown in section. Fig. 7 is a section taken at the line 7 on Fig. 6, and viewed in the direction of the arrow. Fig. 8 is a section 55 taken at the line 8 on Fig. 3, and viewed

in the direction of the arrow. Fig. 9 is an enlarged section taken at the line 9 on Fig. 2, and viewed in the direction of the arrow; and Fig. 10, a section taken at the line 10 on Fig. 9, and viewed in the direction of the 60 arrow.

The machine illustrated comprises, generally stated, a plurality of receptacles 11 for perfume, arranged in the casing 12 of the machine and each equipped with atomizing 65 means 13, through which the perfume, from any one of the several receptacles 11, is sprayed through the front-wall of the machine; air-compressing means 14; coin-controlled mechanism for operating the air-compressing means; and valve-mechanism 15 connected with the air-compressing means and with the several atomizing devices 13, and by the manipulation of which the air from the air-compressor may be directed 70 through any one of the various perfume-receptacles 11.

The receptacles 11 may be in the form of bottles, or in any other desirable form, and in the construction illustrated, are shown as 80 supported on a false bottom 16, in the casing 12, to be exposed to view through an opening 17 in the front side 18 of the casing, the casing, by preference, containing a partition 19, located in the rear of the receptacles 11, and 85 preferably having a mirrored front surface. The atomizing devices 13 each comprise a tube 20, which fits into the cork 21 of the receptacle 11, and opens into the interior of the latter, the tube 20 having a lateral branch 90 22; a relatively small tube 23, which extends at its lower end into the perfume in the receptacle 11, thence upwardly through the tube 20 and its extension 22, from which it is spaced as shown, the tube 22 terminating 95 in a nipple 24. The nipple 24 contains a chamber 25, with which the outer end of the tube section 22 communicates through the medium of an opening 26, formed in a block 27 in the outer end of this tube, the nipple 100 24 fitting at its outer reduced end 26 in an opening 27 in the front wall 18 of the casing, the outer end of the nipple containing a relatively small aperture 28, it being understood that, by preference, a nipple 24 is provided 105 for coöperation with each of the receptacles 11.

A flexible tube 29 connects with the upper end of each tube 20, the tubes 29 being connected at their outer ends with pipe sections 110

30, radiating from the casing 31 of the valve 15, which is secured to the rear side of the casing-front 18, these pipe sections 30 opening into the interior of the valve casing 31. 5 The valve proper of the valve device 15 is represented at 32, this valve being rotatably mounted in the casing 31, and equipped with an operating handle 33, by which it may be rotated, the valve 32 containing a port 34, 10 adapted to be moved at one end into registration with any one of the pipe sections 30. The inner end of the valve 32 connects with a flexible tube 35, which communicates with the other end of the port 34, this tube being 15 connected at its other end with a nipple 36, provided on the upper end of the cylinder 37 of the air compressing device 14, and containing an opening 38 extending therethrough to connect with the pipe 35, and 20 with the interior of the cylinder 37 at the upper end of the latter. The cylinder 37, which is secured to the inner side of the side wall 39 of the casing, to be spaced therefrom, by a plate 40, secured to the casing side 39 by screws 41, and carrying a section 25 42 connected with the cylinder 37, contains a piston 43, the piston rod 44 of which is connected with a block 45 which slides up and down, with the piston, 43, at its reduced section 46, in a slot 47 provided in a plate 48 secured to the inner side of the side wall 39, the wall 39 being cut away, as represented at 30 49, to permit of such movement, the upper surface of the block 45 being preferably horizontal and flat, as represented. 35

In the operation of the mechanism the piston 43 is pulled downwardly to draw into the cylinder 37 a charge of air to be compressed and forced to one of the receptacles 40 11, the piston thereafter being released and quickly returning to normal position to compress the charge for the purpose stated, a spring 50 connected at one end with a lug 51 45 on the cylinder 37, and at its opposite end with the block 45, being provided for producing the quick return of the piston. 45

The following is a description of the coin-controlled mechanism whereby the operation of the piston 43 is controlled: The lever for 50 operating the mechanism is illustrated at 52, this lever being pivoted to the casing wall, as indicated at 53, and extending at its forward end through a slot 52^a, in the front side 18 of the casing, its outer end being 55 equipped with a finger rest 52^b, whereby it may be readily depressed by the operator. A second lever 54, pivoted at its forward end to the casing side 39, as represented at 55, is connected with the lever 52 through the 60 medium of a link 56 which is pivotally connected with these two levers, as indicated at 57 and 58 respectively, whereby when the lever 52 is depressed it will also depress the lever 54. The lever 54 is provided, at its 65 outer end, with a dog 58, having a straight

bottom surface 59 and a curved upper surface 60. The dog is pivoted to the lever 54, as indicated at 61, and is adapted to abut, at its forward end, against a pin 62 on the lever 54. The dog 59, in the normal position 70 of the machine, extends above and partly across the upper surface of the block 45 with which it engages when the lever 54 is depressed, for drawing the piston 43 downwardly, the dog 59 being held against rotation in this movement by its engagement with the pin 62. Slidably confined in bearings 63, provided on the inner surface of the casing side 39, is a vertically disposed slide 64, which is pivotally connected at its lower end with the lever 54, through the medium of a pin 65. A coil spring 66, connected at its upper end with the upper bearing 63 and at its lower end with the pin 65, serves to hold the mechanism, just described, 80 in raised position, Fig. 3, and return it to this position after being fully operated, as hereinafter described. The slide 64 carries two pins 67 and 68, adapted to coöperate with a rock-member 69, as hereinafter described. The rock-member 69 is formed of a side plate 70, which extends at its rear end across and closely adjacent to the face of the slide 64, a bottom plate 71, an end plate 72 at its upper, forward, edge, an outwardly-turned lug 73, and a depending ear 74, at which latter the rock-member 69 is pivotally supported on the casing side 39 by a pin 75. The normal position of the rock-member is that illustrated in Fig. 3, 90 wherein it bears at its lower edge against the pin 68, under the action of a spring 76, secured at one end, as indicated at 77, to the casing side, and at its opposite end, as indicated at 78, to the rock-member 69. The 100 lug 73 is provided for coöperation with the slide 64, which latter contains a notch 79 in its forward edge. In the normal position of the parts, the pin 68 holds the rock-member 69 in the position illustrated in 105 Fig. 3, wherein the lug 73 extends opposite the notch 79, but forwardly of the front edge of the slide 64. 110

Secured to the casing side 39 is a plate 80, provided with a flange 81, spaced from the portion 72 of the rock-member 69, as represented in Figs. 3 and 4, the lower end of the flange 81 and the section 72, when the rock-member is in the normal position illustrated in Fig. 3, being spaced apart a 115 distance slightly less than the diameter of the coin to be used in operating the machine and which is delivered into engagement with the flange 81 and section 72, by introducing it through a slot 82 in the front 120 side 18 of the casing, into a chute 83, in registration with said slot. 125

The operation of the machine is as follows: Assuming the parts of the machine to be in the normal position represented in 130

Figs. 1, 2, 3 and 6 to 10 inclusive, and that the receptacles 11 contain perfume, the operator swings the lever 33 to the right or left in Fig. 1, causing the port 34 to register with the one of the branch pipes 30 connected with the receptacle 11 containing the perfume which it is desired be discharged from the machine, the lever 33, by preference, being provided with a pointer 84 and the casing 18 having marks thereon, for coöperation with the pointer 84, to indicate from which receptacle the perfume will be discharged when the pointer 84 is in registration with such point, these points being indicated at 85, 86, 87 and 88 and having arrows extending therefrom to a position directly opposite the respective receptacles. The operator then deposits a coin, or other token, of the desired denomination, represented at X, into the slot 82, the coin passing through the chute 83 and dropping into the space between the flange 81 and section 72 wherein it becomes lodged, (Fig. 3). The operator then presses down on the lever 52, which depresses the lever 54, the dog 59 engaging the block 45 and causing the piston 43 to descend. The piston 43 continues to descend until the dog 59, in its continued downward movement, moves out of engagement with the block, whereupon the spring 50 forcibly returns the piston 43 to normally raised position and in doing so compresses the air which was drawn into the cylinder 37 on the downward stroke of the plunger, and forces the air thus compressed through the pipe 35, valve 15 and the one of the tubes 29 which is in communication with the port 34 of the valve. A portion of the air thus passed through the tube 29 passes down into the receptacle 11 through the tube 20, and the remaining portion passes through the tube 22, discharging through the opening 26 into the chamber 25. The effect of thus introducing air into these tubes is to cause the liquid in the receptacle 11 to be forced upwardly into the tube 23 and also to be drawn from the outer end of the tube 23, by the rush of air, past the end of the latter, causing the perfume to be atomized and forcing it outwardly, in the form of a spray, through the opening 28. The pin 67 is so arranged that just before the lever 52 reaches the limit of its downward movement, this pin will ride against an inclined edge of the rock-member 69 and rotate the latter on its pivot 75 in a clockwise direction in Fig. 3, with the result of permitting the coin X to become released from engagement with the flange 81 and section 72 of the rock-member and drop through said rock-member into a chute 90, from the lower end of which it discharges into the bottom 65 of the casing.

In the particular arrangement illustrated, means are provided for preventing the return of the lever 52 to normal position, after it has once been operated downwardly, after a coin has been inserted into the chute 83, these means comprising a dog 91, pivotally supported on the casing side 39, as indicated at 92, and a coil spring 93 connected with one end of the dog and with the pin 77, the other end of the dog being 75 in the form of a tooth, represented at 94, adapted to engage the serrated edge 95 of the slide 64.

In the upward movement of the slide 64, after the dog 58 has disengaged from the block 45 and the operator has released downward pressure on the lever 52, the pin 68 strikes the lower edge of the rock-member 69, moving the latter to the normal position represented in Fig. 3, preparatory to receiving another coin, the dog 58, in the upward movement of the lever 54, riding at its beveled upper edge 60 against the block 45, which causes the dog to rotate on the pivot 61 in an anti-clock-wise direction, in Fig. 3, against the action of a coil spring 96, secured to the dog as represented at 97 and to the lever 54, as represented at 98, the dog 58 springing back to normal position, represented in Fig. 3, 95 upon disengaging from said block.

It will be understood from the foregoing that the machine can not be operated unless a coin of the proper denomination, or other suitable token, is deposited in the slot 82, inasmuch as the slide 64, in its downward movement, causes the pin 68 to lower, and unless the rock-member 69 is held against rotation in anti-clock-wise direction in Fig. 3, as it is when a coin is introduced into the machine, the lug 73 will be carried into the notch 79 in the slide 64 and become interlocked therewith, thus preventing the lowering of the slide 64, and consequently preventing the operation of the levers 52 and 54. It may be stated that as soon as the coin X has dropped from the rock-member 69, the spring 76 is free to swing the rock-member in the direction last-referred to, but this does not affect the movement of the slide 64, inasmuch as the lug 73 bears against the smooth forward edge of the latter above the notch 79.

While I have illustrated and described a particular embodiment of my invention, I do not wish to be understood as intending to limit it thereto, as the same may be variously modified and altered without departing from the spirit of my invention.

What I claim as new and desire to secure by Letters Patent, is:

1. In coin-controlled mechanism, the combination of a shiftable member, a second shiftable member shiftable at an angle to said first-named member and having a coin-

engaging surface, a third member having a coin-engaging surface, said shiftable members having portions adapted to engage and prevent movement of said first-named member when said second member is in one position, means on said first-named member for normally holding said second-named member in position for holding a coin between said surfaces and said portions out of engaging position, and means for releasing the coin from said second-named shiftable member after said first-named member has moved a predetermined distance.

2. In coin-controlled mechanism, the combination of a shiftable member, a rock-member having a coin-engaging surface, a third member having a coin-engaging surface, said shiftable member and said rock-member having portions adapted to engage and prevent movement of said shiftable member when said rock-member is in one position, means on said shiftable member for normally holding said rock-member in position for holding a coin between said surfaces and said portions out of engaging position, and means for releasing the coin from said rock-member after said shiftable member has moved a predetermined distance.

3. In coin-controlled mechanism, the combination of an automatically-returnable shiftable member, a second shiftable member shiftable at an angle to said first-named member and having a coin-engaging surface, a third member having a coin-engaging surface, said shiftable members having portions adapted to engage and prevent movement of said first-named member when said second member is in one position, means on said first-named member for normally holding said second member in position for holding a coin between said surfaces and said portions out of engaging position, means for actuating said first-named member, and means for releasing the coin from said second-named shiftable member after said first-named member has moved a predetermined distance.

4. In coin-controlled mechanism, the combination of a shiftable member, a second shiftable member shiftable at an angle to said first-named member and having a coin-engaging surface, a third member having a coin-engaging surface, said shiftable members having portions adapted to engage and prevent movement of said first-named member when said second member is in one position, means on said first-named member for normally holding said second-named member in position for holding a coin between said surfaces and said portions out of engaging position, and means actuated by said first-named member for shifting said second-named member to a position in which the coin will discharge from the latter.

5. In coin-controlled mechanism, the com-

bination of a shiftable member, a second shiftable member shiftable at an angle to said first-named member and having a coin-engaging surface, a third member having a coin-engaging surface, said shiftable members having portions adapted to engage and prevent movement of said first-named member when said second member is in one position, means tending to move said second member into a position in which said portions engage, means on said first-named member operating to normally hold said second member in a position in which said portions are out of engagement and in a position for holding a coin between said surfaces, in opposition to said first-named means, and means for releasing the coin from said second member after said first-named member has moved a predetermined distance.

6. In coin-controlled mechanism, the combination of a shiftable member, a rock-member having a coin-engaging surface, a third member having a coin-engaging surface, said shiftable member and rock-member having portions adapted to engage and prevent movement of said first-named member when said rock-member is in one position, means tending to move said rock-member to a position in which said portions engage, means on said first-named member for normally holding said rock-member in position for holding a coin between said surfaces and said portions out of engaging position, against the action of said first-named means, and means actuated by said first-named member for rocking said rock-member to a position for releasing the coin therefrom after said first-named member has moved a predetermined distance.

7. In coin-controlled mechanism, the combination of a longitudinally reciprocal member, a shiftable member having a coin-engaging surface, a third member having a coin-engaging surface, said first two referred to members having portions adapted to engage and prevent movement of said first-named member when said second member is in one position, means tending to rock said second member to a position in which said portions engage and the coin-engaging surface on said second member moves toward said third member, means on said first-named member for normally holding said second member in position for holding a coin between said surfaces and said portions out of engaging position, and means actuated by said first-named member after a predetermined movement thereof, for shifting said second-member to a position in which the coin therein will discharge.

8. In coin-controlled mechanism, the combination of a longitudinally-movable member, a rock-member having a coin-engaging surface, a third member having a coin-en-

gaging surface, said first two referred to members having portions adapted to engage and prevent movement of said first-named member when said rock-member is in one position, means tending to rock said rock-member to a position in which said portions engage, and in a direction to move the coin-engaging surface on said rock-member toward said third member, means on said first-named member operating to normally hold said rock-member in a position for holding a coin between said surfaces and said portions out of engaging position, and means on said first-named member operating after a predetermined movement of the latter to rock said rock-member to a position in which the coin will release therefrom.

9. In coin-controlled mechanism, the combination of a longitudinally-movable member automatically returnable to normal position, a rock-member having a coin-engaging surface, a third member having a coin-engaging surface, said first two referred to members having portions adapted to engage and prevent movement of said first-named member when said rock-member is in one position, means tending to rock said rock-member to a position in which said portions engage and in a direction for moving the coin-engaging surface on said rock-member toward said third member, means on said first-named member operating to normally hold said rock-member in position for holding a coin between said surfaces and said portions out of engaging position, said rock-member being provided with a cam surface, means on said first-named member adapted, when the latter is actuated, to engage said cam surface and rock said rock-member to a position in which the coin releases therefrom, and means for actuating said first-named member.

10. In coin-controlled mechanism, the combination of a longitudinally-movable member carrying projections spaced apart, a spring tending to move said member in one direction, a rock-member having a cam surface and a coin-engaging surface, a third member having a coin-engaging surface, said first two referred to members having portions adapted to engage and prevent movement of said first-named member when said rock-member is in one position, a

spring tending to move said rock-member to a position in which said portions engage and in a direction for moving the coin-engaging surface on said rock-member toward said third member, one of the projections on said first-named member operating to engage said rock-member and hold it in a position against the action of said spring in which said portions are out of engagement and the coin may be held between said coin-engaging surfaces, and said other projection adapted to rock said rock-member, after a predetermined movement of said first-named member, to a position in which the coin releases from said rock-member, and means for actuating said first-named member.

11. In coin-controlled mechanism, the combination of a shiftable member, a second shiftable member shiftable at an angle to the former, a third member having a coin-engaging surface, said shiftable members having portions adapted to engage and prevent movement of said first-named member when said second member is in one position, means on said first-named member for normally holding said second-named member in position for holding a coin between said surfaces and said portions out of engaging position, said second-named member having a cam-surface, and means actuated by said first-named shiftable member and engaging said cam surface for moving said second-named shiftable member to a position to release the coin therefrom.

12. In coin-controlled mechanism, the combination of a movably-mounted, automatically-returnable member, a lever pivotally supported at its forward end and adapted, when actuated, to directly engage at its rear end with said member and during such actuation release from the latter, a second lever pivotally supported at its rear end and extending at its opposite end into a position to be actuated, a link connecting said levers together between said pivots to effect rotation of said levers on their pivots simultaneously in opposite directions, and coin-controlled means controlling the actuation of said levers.

HERBERT S. MILLS.

In presence of—
 E. C. CHALDER,
 JAMES HOROWITZ.
